UNITED STATES PATENT OFFICE.

ALDEN M. DRAKE AND WALDO J. GUILD, OF WORCESTER, MASSACHUSETTS, AS-SIGNORS TO THE HEALD MACHINE COMPANY, OF WORCESTER, MASSACHUSETTS, A CORPORATION OF MASSACHUSETTS.

GRINDING MACHINE.

Application filed January 11, 1924. Serial No. 685,577.

The present invention relates to grinding machines and contemplates certain improvements and refinements in the automatic mechanism which procures relative reciprocatory movement between the work and the grinding wheel,—the objects being (1) to facilitate a rapid withdrawal of the wheel from the work, or vice versa, when it is desired to give access to the work for gauging or for replacement, and (2) to make provision, at the same time, for a short withdrawal movement, without increase of speed, in order to subject the wheel at intervals to a dressing and truing operation.

The several features of the invention, by which the above and other objects are attained, are fully set forth hereinafter, reference being had to the accompanying drawings in which—

Fig. 1 is a view in side elevation of so much of a grinding machine as is necessary to disclose the invention.

Fig. 2 is an enlarged detail view of the arrangement of dogs or stops shown in Fig. 1.

Fig. 3 is an end view of the parts shown in Fig. 2.

Figs. 4 and 5 are sectional views on the lines 4—4 and 5—5 respectively, of Fig. 2.

Fig. 6 is a fragmentary detail view of the latch connection shown in Fig. 2.

Like reference characters refer to like parts in the different figures.

Referring first to Fig. 1, the invention is here shown by way of example in connection with the reciprocating table or carriage 1 of an internal grinding machine. In such a machine, either the grinding wheel or the work to be ground may be carried on the table 1, the reciprocations of the latter being utilized in either case to produce a relative traversing movement between the grinding wheel and the work. As here shown, the table 1 supports and carries a wheel head 2 of ordinary construction,—the work supporting head 3 being carried by a bridge 4 which spans the slideways provided by the machine frame for the movement of the table 1. Back and forth movement of the table 1, to cause the rotating grinding wheel 5 to make the required interior traverse of the rotating work piece 6, may be imparted in any well known manner, as for instance, by the use of the fluid pressure controlling and re-

versing mechanism which forms the subject 55 matter of the copending application of Heald and Guild, Serial No. 629,882, filed April 4, 1923. Such mechanism, or its equivalent, forms no part of the present invention and a detailed description thereof is therefore unnecessary; it is sufficient to note, for the purposes of the present application, that the type of drive adopted for the actuation of the table 1, be it hydraulic drive, or gear drive, or any other type, procures the reversal of the table at each end of its working stroke by the use of spaced adjustable table dogs 7 and 8, adapted to alternately engage and move an interposed member 9, whose position controls the direction of table 70 travel.

In the normal operation of the machine, with the grinding wheel 5 in contact with the work 6, the table 1 will be reversed at each successive engagement of the member 75 9 by the dogs 7 and 8, which dogs obviously are spaced apart on said table a distance substantially corresponding to the working stroke of the grinding wheel, i. e., the length of the hole in the work 6. In the operation of an internal grinding machine such as here shown, there is frequent necessity for interrupting the grinding operation in order that the operator may size or plug the hole which is being ground; such action by 80 the operator, and also the removal of work from the machine and the introduction of a new piece, requires the wheel and the work to be separated axially or longitudinally, in order to give access to said work. In the 85 machine herein illustrated, this separation is obtained by continuing the movement of the table 1 to the right, and for this purpose, the dog 8 is so constructed that it can be passed over the member 9, whenever desired, 90 without effect on said member, the latter remaining in the position illustrated in Fig. 1, which is the position given it by the dog 7, on the preceding stroke of the table 1, to inaugurate movement of said table to the right. 95

To this end, the dog 8 is made in the form of a lever pivoted at 10 to its carrying block 11, with said pivoted end normally bearing by gravity against a stop or ledge 12 on said block, whereby to dispose the other or striking end of said dog 8 in position to engage the member 9. The elevation of the striking end of dog 8, to cause it to pass inoper- 100 105

atively over the member 9, is accomplished by interposing in the path of said dog, just before it reaches the member 9, the upwardly inclined cam surface 13 of a member 14, which is carried by a vertically slidable rod 15 passing through a bracket 16 on the front of the machine. The rod 15 normally occupies the inoperative position illustrated in Fig. 2, with the cam surface 13 just below and out of the path of the dog 8; by its connection, at 17, to a treadle 18 pivoted at 19 to the base of the machine, the rod 15 is adapted to be elevated by foot pressure applied to said treadle, and this movement which, it is to be particularly noted, leaves both of the operator's hands free to give such attention as may be desired to the work, results in the dog 8 riding up the cam surface 13, so as to clear the top of the member 9. This obviously prevents the reversal of the table 1, which would otherwise take place at its right hand limit of working reciprocation,—the right hand movement being continued so as to withdraw the grinding wheel altogether from the work zone at an accelerated rate of movement, as hereinafter described.

If desired, the above described interposition of the cam surface 13 may be accomplished by hand rather than by operation of the foot treadle 18. To this end, the member 14 is equipped with a projecting handle 20, in convenient position to be seized and drawn upwardly by the operator along with said member and its attached rod 15,—the limit of upward movement, both in the case of hand operation and treadle operation, being determined by a collar 21 on rod 15, which engages the under side of the bracket 16. To adapt the above described mechanism to machines whose bases are elevated at different levels from the level at which the operator stands, the treadle 18 is made in the form of a bell crank lever, with a foot engaging portion 22 on each side. If the operator stands on the supporting floor, the treadle is so disposed as to slope its longer arm downwardly, as shown in full lines in Fig. 3; on the other hand, if an operating platform, above the floor level, is used, said treadle is reversed, as shown by the broken lines in Fig. 3.

The carrying block 11 and the pivoted dog 8 support also an elongated bar or cam 23, Fig. 2, the right hand end of which is spaced from the striking end of dog 8 by a distance slightly less than that between the top of member 9 and a cam roller 24, Fig. 1, carried by the end of an arm 25. In the normal working reciprocations of the table 1, when the grinding wheel is in contact with the work, the roller 24 is not reached by the bar or cam 23, since the dog 8 will always strike the member 9 to reverse the

table, when the cam and roller are still a little distance apart. However, when the dog 8 is lifted by the operator, as above described, to pass over the member 9 and thereby inaugurate a non-working movement of the table 1 to the right, the bar or cam 23 will engage the roller 24 to depress the arm 25. This depression of the arm 25 is availed of to produce an increased speed of travel for the table 1, either in the manner described in the aforesaid copending application of Heald and Guild, or in any other well known manner. The purpose of this is to automatically accomplish the right hand non-working movement of table 1 at the maximum speed, irrespective of the speed selected for the working movement when the grinding wheel is in contact with the work; this eliminates any unnecessary loss of time in moving the grinding wheel away from the work, since the bar or cam 23 maintains its engagement with the roller 24 throughout the entire withdrawal movement, thus automatically maintaining the high speed table travel until the table is brought to rest at the end of said right hand movement, as fully described in the aforesaid application of Heald and Guild.

While such high speed table travel is especially advantageous when free access to the work 6 is desired, the opposite of this is true in other instances requiring withdrawal of the grinding wheel 5 from the work, as when subjecting said wheel to the action of a dressing or truing device 26, Fig. 1, which may be carried by the usual bridge 27. Such dressing and truing, which is frequently resorted to in the operation of grinding, requires only a limited withdrawal movement of the wheel from the work, and is an operation wherein it would be most undesirable for the traverse of the wheel to take place at high speed. To fulfill these conditions therefor, provision must be made for a wholly different character of wheel withdrawal from that above described, which involves the inoperative passage of dog 8 over member 9 and the ensuing prolonged right hand movement of table 1 at maximum speed; the withdrawal for dressing or truing, which must be selectively available to the operator of the machine along with the first described withdrawal, involves only a short right hand movement of the table 1, and this at a speed no higher than the relatively slow traverse of the wheel in contact with the work.

To this end, it is proposed to make the dog 8 readily shiftable to the left from its normal working position, so as to give an increase, when desired, in the right hand throw or stroke of table 1 sufficient to carry the wheel 5 past the dresser 26. Instead of securing the block 11 of dog 8 directly to the table, as is done in the case of the dog 7, said

- block 11 is operatively and removably connected, in spaced relation, to a block 28, the latter, in common with the block 29 of dog 7, having the usual set screw device 30 for 5 adjustably securing it at any desired position longitudinally of the edge of table 1. The connection between the block 28 and the block 11 is a latch lever 31, pivoted at 32 to the block 11, and having a shoulder 10 33 in its free end which abuts a projection or boss 34 on the block 28, with the other side of said boss engaged by a handle 35 of said lever. In this position of the parts, the latch lever 31 holds the block 11 in 15 definite spaced relation to the block 28, and in adjusting the dog 8 to procure any desired working stroke of the table, the block 28, instead of the block 11, is the part that is moved and that is secured in the desired 20 position of adjustment along the edge of the table.
- When the operator desires to have the grinding wheel 5 carried past the dresser 26, in order to true the surface of said wheel, 25 he simply seizes the handle 35 on the latch lever 31 and lifts the shoulder 33 and handle 35 away from boss 34; this makes the block 11 freely slidable, to be drawn by the operator or pushed by the member 9 to the left, 30 until the adjusting screw 8' of dog 8 abuts a projection 28' of block 28. This action increases the right hand throw of table 1 by postponing the operative pressure of dog 8 against member 9, and the amount of such 35 increase is sufficient to carry the grinding wheel 5 past the dresser 26. However, no increase in the speed of said table is produced, since the bar or cam 23, being secured to the block 11, moves to the left with it and 40 does not reach the roller 24, notwithstanding the increased right hand travel of the table. After the grinding wheel 5 has been passed a sufficient number of times in contact with the dresser 26, the operator pushes the latch 45 lever 31 to the right and restores the operative connection between the notch 33 and the boss 34, thereby holding the blocks 11 and 28 in the predetermined spaced relation that causes the wheel 5 to make its regular 50 working stroke. The pivotal connection of the latch lever 31 to the block 11 may be made at any one of a plurality of different holes 36 in said block, in order to vary, as desired, the spacing between blocks 11 and 55 28, and thereby give greater or less amplitude to the slow speed withdrawl movement availed of for the purpose of dressing the wheel. Obviously, the latch lever may be pivoted to the block 28, instead of to the 60 block 11, in which case the latch engagement would be with the block 11.
- We claim,
1. In apparatus of the class described, a reciprocatory table, a member shiftable in opposite directions to procure the reversals 65 in the movement of said table, adjustable stops carried by said table for engaging and shifting said member, one of said stops being pivotally mounted and maintained by gravity in its operative position, and fixed 70 position operator controlled means for interposing a cam surface in the path of said stop, to swing it into inoperative position.
  2. In a machine of the class described, a reciprocatory table, adjustable stops on said table for reversing the movement of the table at each end of its travel, and a treadle, pivoted at the base of the machine, and adapted when actuated to render one of said stops inoperative, said treadle being of 75 bell-crank form, whereby its reversal accommodates it to machine bases at different heights from the operating floor.
  3. In apparatus of the class described, a reciprocatory table, a member shiftable in 80 opposite directions to procure the reversals in the movement of said table, adjustable stops carried by said table for engaging and shifting said member, one of said stops being slidable away from the other stop, to temporarily increase the travel of said table, together with a latching member which automatically identifies the previous position of the stop and checks it there.
  4. In apparatus of the class described, a reciprocatory table, a member shiftable in 85 opposite directions to procure the reversals in the movement of said table, a block adjustably secured to said table, and a pair of stops carried by said table for engaging and shifting said member, one of said stops being adjustably secured to said table, and means for releasably holding the other in predetermined spaced relation to said block.
  5. In a grinding machine, a reciprocatory table, a member shiftable in opposite directions to procure the reversals in the movement of said table, and a pair of adjustable stops carried by said table for engaging and shifting said member in the normal 90 movements of said table, in combination with means to remove one of said stops from the path of said member, thereby procuring the movement of said table to non-working position, and means operable from a fixed position to delay the operation of said member by said stop, thereby increasing the throw of said table in one direction.
  6. In a grinding machine, a reciprocatory table, a member shiftable in opposite directions to procure the reversals in the movement of said table, and a pair of adjustable stops carried by said table for engaging and shifting said member in the normal working movements of said table, in 95 combination with means for procuring the travel of said table at increased speed away from working position, by passing said member with one of said stops, and means operable from a fixed position for increas-

ing the working throw of said table, without increasing its speed, by shifting said stop.

7. In a grinding machine, a reciprocating table, a stop carried by said table and operable on a shiftable member to limit the table movement in one direction, a member moving with said stop and rendered operative when said shiftable member is passed by said stop, to increase the speed of said table on its ensuing non-working travel, and means for shifting said stop, which then operates said shiftable member, to increase the working throw of said table without increasing its speed.

8. In a grinding machine, a table carrying the grinding wheel, and adapted to reciprocate, to traverse the work with said wheel, a stop carried by said table for limiting the travel of the wheel in one direction, means for rendering said stop inoperative, to procure complete withdrawal of said wheel from said path, means moving with said stop for increasing the speed of said table on said withdrawal movement, and means for shifting said stop, to increase said path of travel, without increasing the speed of said table.

9. In a grinding machine, a rotary grinding wheel and a work holding device, a reciprocating table on which one of said parts is carried, a reversing element to cause the reciprocations of the table to be reversed, a pair of dogs carried by the table to actuate the reversing element, a clamping member adapted to be adjustably clamped to said table and means holding one of said dogs disengageably a fixed distance from said clamping member.

10. In a grinding machine, a rotary grinding wheel and a work holding device, a re-

ciprocating table on which one of said parts is carried, a reversing element to cause the reciprocations of the table to be reversed, a pair of dogs carried by the table to actuate the reversing element, a clamping member adapted to be adjustably clamped to said table, and a bar with a shoulder thereon, said bar engaging said clamping member and one of said dogs, whereby one of said dogs can be disengageably held a fixed distance from said clamping member.

11. In a grinding machine, a rotary grinding wheel and a work holding device, a reciprocating table on which one of said parts is carried, a reversing element to cause the reciprocations of the table to be reversed, a pair of dogs carried by the table to actuate the reversing element, an adjustable clamping member, one of said dogs being slideable on ways, and releasable means holding said slideable dog a fixed distance away from said clamping member.

12. In a grinding machine, a rotary grinding wheel and a work holding device, a reciprocating table on which one of said parts is carried, a reversing element to cause the reciprocations of the table to be reversed, a pair of dogs carried by the table to actuate the reversing element, a clamping member and a disengageable spacing member, one of said dogs being slideable on ways and being releasably held on said ways a fixed distance away from said clamping member by said spacing member, whereby said dog may be held at said fixed distance or allowed to slide along said ways to a predetermined point.

Dated this 22nd day of December, 1923.
